U. S. PATENT OFFICE.

No. 1,347.

1861.

WHOLE No. 32,351.

Sled Brake.

ALBERT S. CLARK, OF DRYDEN, N. Y.

Letters Patent No. 1,347, dated May 21, 1861.

SPECIFICATION.

TO ALL WHOM IT MAY CONCERN:

Be it known, that I, ALBERT S. CLARK, of Dryden, in the county of Tompkins, in the State of New York, have invented a new and improved Sled Brake; and I do hereby declare that the following is a full and exact description of the same, reference being had to the annexed drawings, making a part of this specification, in which—

Fig. 1 is a plan view or longitudinal elevation.

The nature of my invention consists in providing a sled or sleigh with a brake of such construction as to operate with great power, and at the same time to require but slight exertion from the operator to keep it in a most effectual position.

To enable those skilled in the art to fully understand and construct my invention, I will proceed to describe it.

A represents a sled of ordinary construction. B is the lever for operating the brake, which is secured to the rocking bar C by being inserted in a hole made therein. Through the rave b b a longitudinal slot is made for the admission of the lever B, and to provide for it sufficient room to operate. C is a rocking bar, secured to the rave b b by means of suitable bearings, as at a.

E is a link connected to the arm c of the rocking bar C, and also to the claw f, by the arm D. The arm D and claw f are made of one piece and secured to the runner G, in any proper manner that will admit of a free play upon its fulcrum o. s is a slot in the arm D, through which the pin i passes loosely, so as to admit of a sliding motion, and is secured by riveting the ends upon each side of the link E. H is the middle beam of the sled, with which the link E comes in contact when operated, and serves as an effectual means of keeping down the claw f.

Clark's Improved Sled Brake.

In the above description it will be seen that by throwing forward the lever B, it actuates the claw f by the movement of the link E, which operates in the slot s of the arm D, as an inclined plane, and is held down by sliding under the projecting beam H. The lever B is fitted into the rocking bar C, with a tapering form, which admits of its being easily withdrawn when logs or other heavy loading is required to be rolled on the sled, and replaced with facility when required.

What I claim as new, and desire to secure by Letters Patent, is—

The combination of link E and beam H with the slotted arm D, the whole being constructed and arranged as and for the purpose herein shown and described.

ALBERT S. CLARK.
